CLAIM

The ornamental design for a security system hub, as shown and described.

DESCRIPTION

The file of this patent contains at least one drawing/photograph executed in color. Copies of this patent with color drawing(s)/photograph(s) will be provided by the Office upon request and payment of the necessary fee

FIG. 1 is a front top perspective view of a security system hub showing our new design;

FIG. 2 is a front top perspective view thereof, showing the article in an alternate configuration in use;

FIG. 3 is a top plan view thereof;

FIG. 4 is a rear elevational view thereof; and,

FIG. 5 is a front elevational view thereof.

The broken lines shown in the drawings represent portions of the security system hub that form no part of the claimed design.
